CLAIM

I claim the ornamental design for a water bottle with carrier, as shown.

DESCRIPTION

FIG. 1 is a side-elevational view of the water bottle with carrier of this invention.

FIG. 2 is a top view of the water bottle.

FIG. 3 is a bottom view of the water bottle; and,

FIG. 4 is a side-elevational view of the water bottle, at a right angle to the view of FIG. 1. All side views of the water bottle carry the same design.
